(57) CLAIM

The ornamental design for a trailer body, as shown and described.

DESCRIPTION

FIG. 1 is a perspective view of a trailer body of the present invention;

FIG. 2 is a front elevation view thereof, the rear elevation view being a mirror image thereof;

FIG. 3 is a left side elevation view thereof, the right side elevation view being a mirror image thereof;

FIG. 4 is a top plan view thereof; and,

FIG. 5 is a bottom plan view thereof.

The broken lines shown in FIGS. 1 and 2 are for illustrative purposes only and form no part of the claimed design.
